ABSTRACT OF THE DISCLOSURE

Entire internal threads and grooves are simultaneously cold formed in workpieces by the use of an expandable cylindrical sleeve or segment chasers. A supporting shaft is provided with conical portions adapted to receive the sleeve or the segment chasers and to guide their thread-forming portions into a workpiece.

The purpose of the present invention is a new method to obtain internal threads and grooves by cold forming.

A further object of this invention are the devices or tools used to realize this method, essentially constituted of threading elements in the shape of a one-piece sleeve, or individual chaser combs alternatively and guided by conical supports.

The conventional method to obtain internal threads or grooves is the use of cutting tools, known by the name of taps. The inconveniences presented through the use of such tools are among others, the rapid loss of cutting edge, the difficulty of correct resharpening and the frequent occurrence of enlarged threads, notably at the beginning of the threads. Furthermore, the lubricating and cooling oil can be hardly reused because of its mixing with the chips resulting from the cutting operation.

Another known process is of cold forming. To accomplish it, the tools usually employed are subject to a lot of disadvantages.

In effect, the tools used in the process above referred are the so called solid cold forming taps of polygonal section, with a conical point that enters the hole to be threaded, the diameter of which is approximately equal to the pitch diameter of the desired threads. The tools are forced through the extension of the hole the thread resulting formed, under cold conditions.

The solid taps do not permit recuperation, it being frequently seen that they are worn out not uniformly over their length; also it frequently becomes difficult to obtain uniform threads at the entrance of the internal threads.

Further, it is suitable to cite that all type of tools until now known are of a high cost of production because of their special polygonal configuration associated with reduced durability and high cost of the steel they must be made of.

Besides, these taps only permit obtaining standardized threads, and in the eventual need for internal threads of over-standard or sub-standard dimensions, the manufacture of special taps at a greatly increased price or cost is required.

Still another disadvantage of these taps resides in the difficulty to obtain the desired concentricity and parallelism between the geometric axis of the hole and the axis of the thread made in it.

A further disadvantage peculiar to the taps until now employed is the necessity of these to be withdrawn from the hole by rotation thereof that is to say they must be unscrewed after forming the screw thread.

The main object of the present invention is to provide a method of obtaining internal threads or grooves of whatever diameter and longitudinal dimension by means of

2

cold forming (without cutting) obtaining a thread uniformity, and coincidence of the center line of the hole with the center line of the thread.

Another object of this invention is the provision of two basic types of tools, needed to accomplish the cold forming process. These tools are essentially constituted by a conical guiding pin which supports the threaded forming element (which, as stated before, can be an expandable sleeve or a set of chasers). This thread forming element moves axially alongside the guiding pin under the effect of a force applied parallel to the axis of the pin. Thus, it causes the expanding of the threading element and the subsequent deformation of the internal walls of the hole in which it was introduced, cold forming the thread.

It is obvious that the problems of the lack of parallelism and concentricity presented through tools used to date can be avoided. The employment of this new method and related devices is specially recommendable for mass production.

A simple mechanism may be used to support the tool and to give it the proper movement of oscillation. Then a source of power—mechanical, hydraulic or pneumatic—is applied to the threading device with force necessary to expand the device to the predetermined diameter for the cold forming of internal threads or grooves.

A fixture will hold the work-part in alignment with the tool, not permitting angular movement.

It follows that the purpose of this invention is to present a method, and the means to realize it: to tap by cold forming method internal threads and grooves of whatever type, dimension and diameter desired such as buttress thread, standard threads and others without limitation of diameter size or longitudinal dimension, including left hand threads and taper threads.

This operation is economically and technically more advantageous because the internal threads thus obtained comply with minimum tolerances and have a better finish.

Still another purpose is to supply threading devices of tools of greater durability, since these tools, have no cutting edges.

Another object of this invention is to provide internal threads with over-standard and under-standard diameters, thus reducing quantitatively the number of necessary tools to cover the most varied range of internal thread diameters.

Another advantage lies in the fact that while the cutting of the material is eliminated, there are no chips produced during the cold forming process, preventing the tool to get stuck and permitting total reuse of the lubricating-cooling oil without previous filtering.

Still another advantage is represented by the acceleration of the operation of internal threading, since the unscrewing of the forming tool is not required, it being sufficient to ease the force applied to the threading element to permit its contraction and consequent axial withdrawal from the threaded hole, without the threads being touched by the forming tools. This characteristic is one of the most important, qualifying the tool of this invention for top production.

A final advantage lies in the economic aspect of the invention, considering the high level production and the possibility of reusing the tools by successive reconstitution of the cold forming elements, giving longer durability and lower manufacturing cost.

It is possible to produce internal threads by this method of cold forming in most ferrous metals—including stainless steel—as well as in many of the non-ferrous metals such as brass, copper, aluminum and others.

The invention will be better visualized in the light of the attached drawings showing two alternative embodiments of the tools to realize the method of this invention.

FIG. 1 is a broken elevation of a device to accomplish the method of this invention.

FIG. 2 is a lateral view of the same device mounted in its non-operative condition.

FIG. 3 is a lateral view of FIG. 2 showing the tool in working conditions.

FIG. 4 is a broken view of an alternative embodiment of the device to accomplish the process of this invention.

FIG. 5 is a cross section view through lines IV—IV of FIG. 4.

FIG. 6 is a lateral view of FIG. 4 in non-operative conditions, but at the beginning of the operation.

FIG. 7 is the same view of FIG. 6 with the threading element in final working conditions.

From the attached drawings it is verified that the device for tapping or cold forming of internal threads, object of the present invention, is essentially composed of two concentric elements (FIG. 1) one being a core, constituted by an axle 1 with an extremity conically shaped 2 over which slides axially cylindrical sleeve 3, having internal passage for the conical end of axle 1.

Said sleeve or bushing is externally provided with an intermediate threaded area 5 interrupted by longitudinal slots 6 that, in number, are proportional to the dimensions of the bushing, itself.

The bushing is driven while sliding over the conical extremity 2, by means of radial pins 7 projecting through the slots 6.

To start the threading operation the expandable bushing 3 is assembled to the shaft 1, being freely introduced into the orifice 8 of the workpiece 9 (FIG. 2). The external diameter of the threaded sector 5 is smaller upon entry than the pitch diameter of the thread to be obtained in the hole of the workpiece 9 while the diameter of the hole 8 is about the same as the pitch diameter of the thread to be cold formed.

Once the device is inserted into the workpiece 9 an oscillating movement is given to the drive shaft with amplitude of about 90°. The same movement is transmitted to the bushing 3 solidarized to the shaft 1 through the pins 7 inserted into the slots 6, of the said bushing 3.

At the same time when the alternating angular rotation is being executed, a force F is applied to the sleeve 3 in the longitudinal direction parallel to the geometric axis of the assembly. This causes the sliding of the bushing 3 alongside the drive shaft 1 originating the progressive expansion of the bushing 3 and consequently, the greater penetration of the forming threads 5 into the internal surface 8 of the hole, displacing the material under cold condition thus forming, the desired internal thread.

When the above operation is over, it is enough to ease the pressure exercised through the force F by which the threads 5 of the bushing are disengaged from the internal threads permitting removal of the bushing, now contracted to its original dimensions, from the workpiece 9, while the drive shaft 1 is still in movement.

The described operation should be executed preferably by means of a simple mechanism that permits holding the workpiece 9 as securely desirable, while it does not allow angular movement, and also permits the oscillating movement of the tool with contemporaneous application of the force F by the pneumatic or hydraulic mechanism means.

In the remaining figures (4 to 7), an alternative embodiment of the tool is illustrated for cold forming of inside threads or grooves in accordance with this invention, conserving basically the conception of an expansion threading element that slides axially alongside the frusto-conical extremity of a supporting shaft.

FIG. 4 shows the axle 11 whose free extremity is provided with a cylindrical enlargement 12 (FIG. 5) longi-

tudinally cut with channels 13 of which the bottom surfaces 14 are inclined forming in the whole an internal tapering stem shape (FIGS. 4 and 5).

In the same channels, chaser combs 15 are assembled with a sliding adjustment, having as many chasers as the number of channels. The assembly is made in a predetermined sequence.

The chasers have a working surface constituted of thread segments which correspond to the internal thread or groove desired. The segments of thread have a rather thin edge to permit an easier penetration in the workpiece. Each chaser has, following the work zone, a depression 17 ending with an enlargement 18 (FIG. 4). All chasers are guided by the bottom 14 of the channels 13.

Once the oscillating movement R of the arbor 11 is started, with a maximum amplitude of 90°, the force F is also applied in the longitudinal direction parallel to the axle (FIG. 7) by means of an outer flange 21 and inner flange 21a, thus assuring a uniform distribution of pressure on all the chasers 15 and of its regular advance through the guide channels 13 pressing with progressive intensity the material of the workpiece 20 until the desired internal thread is completed under cold conditions.

Once the operation is finished, it is sufficient to ease the pressure resulting from the application of force F permitting the free withdrawal of the tool by means of the sliding of the chaser combs alongside the respective channels and consequent retraction of these chasers without touching the newly formed screw threads.

It is obvious that the length of the total threaded part 5 of the bushings 3 and 16 of the chasers is dimensioned in such a way that it would always be bigger than the longitudinal dimension of the threads to be made, which in the majority of the case is less than 1½ times the diameter of the hole.

It is obvious that the invention has been merely exemplified in the attached drawings as disclosed hereinbefore, which do not constitute a limitation to its scope it being well possible, for instance, to provide a further embodiment of the tool to be used in a rotary movement, instead of alternate angular rotary movement, it being enough to make suitable beveled arrangement of the first threads of the tool.

I claim:

1. A method of swaging internal threads within an opening provided in a workpiece comprising the steps of placing an expandable swaging tool therewithin and then subjecting said tool to simultaneous rotary and expansion movement so that radial and torque forces are applied on the entire forming surface of said opening until said threads are fully formed.

2. A method as described in claim 1 including initially placing said tool within said opening in a retracted position, applying, gradually, an axial force during said rotary movement until the tool is fully expanded so as to form the entire surface to be threaded in one operation, and thence releasing the axial force so as to retract said tool, and thence withdrawing said tool from said opening.
